UNITED STATES PATENT OFFICE.

WILLIAM L. KANN, OF ALLEGHENY, PENNSYLVANIA.

APPLYING ABRASIVE MATERIALS.

SPECIFICATION forming part of Letters Patent No. 588,441, dated August 17, 1897.

Application filed September 30, 1895. Serial No. 564,075. (No model.)

To all whom it may concern:

Be it known that I, WILLIAM L. KANN, of Allegheny, in the county of Allegheny and State of Pennsylvania, have invented a new 5 and useful Improvement in Applying Abrasive Materials, of which the following is a full, clear, and exact description.

My invention relates to the movable tables or disks upon which is thrown a comminuted 10 metallic abrasive employed for grinding or polishing glass, stone, or other material which is applied to the abradent-covered surface; and it consists in providing magnets for holding the abrasive in place upon the disk or 15 table while the article to be ground or polished is applied to the abradent-covered surface.

In the drawings, in which the figure is a 20 diagrammatic view illustrating one form of my improved apparatus, 2 is a rotatory grinding-table secured to the shaft 3 and having fastened to its lower face electromagnets 4 and 5, which create a magnetic field at the 25 upper face of the plate, the plate becoming magnetic and holding the abrasive particles in place thereon until they are worn out, or as long as desired. The current may be led to the magnets by any suitable means, the device shown consisting of a circular 30 plate 6, secured to and revoluble with the shaft, this plate carrying two insulated metallic rings 7 and 8, the ring 7 being connected to the magnet 4, while a return-wire leads from the magnet 5 to the ring 8. These 35 rings are embedded in insulating material 9 and with their lower faces contact the spring-brushes 10 and 11, secured to concentric insulated rings 12 and 13. The rings 12 and 14 are stationary and embedded in insulating 40 material 14, and to them lead the positive and negative wires from a dynamo 15 or other source of electricity.

The action is apparent. The table being rotated and the current switched on it flows up through one set of rings and brushes to 45 one magnet, thence through the table to the other, and thence back through the other set of rings and brushes.

When the metallic abrasive material is thrown upon the table, it is held thereon by 50 the force of magnetism and its full abrasive power exhausted.

The advantages of my invention result from the small amount of abrasive necessary and the reduction in the cost consequent thereon. 55 The only refuse flowing away consists in the particles of the stone, glass, or other material operated upon, and the amount of labor in storing and feeding the abrasive is greatly reduced.

The table may be arranged vertically, if desired, and many other changes may be made in the particular machine employed, since

What I claim is—

1. In a grinding and polishing apparatus, 65 the combination of a movable table or disk, to the upper face of which is applied a metallic abrasive, and magnets arranged to hold the abrasive in place thereon.

2. In grinding and polishing apparatus, the 70 combination with a rotary table or disk arranged to receive a metallic abrasive, and to which the article is applied, of magnets secured to and rotatory with the table, which constitutes their pole-piece, substantially as 75 described.

In testimony whereof I have hereunto set my hand.

WILLIAM L. KANN.
